UNITED STATES PATENT OFFICE.

CHARLES O. MARX, OF BROOKLYN, NEW YORK, ASSIGNOR OF ONE-HALF TO SAMUEL BRUCKHEIMER, OF NEW YORK, N. Y.

DOOR-HANGER.

1,041,833.

Specification of Letters Patent. Patented Oct. 22, 1912.

Application filed April 19, 1912. Serial No. 691,927.

To all whom it may concern:

Be it known that I, CHARLES O. MARX, a citizen of the United States, residing at Brooklyn, in the county of Kings and State 5 of New York, have invented new and useful Improvements in Door-Hangers, of which the following is a specification.

This invention relates to door hangers, and has special reference to door hangers 10 for supporting and operating heavy sliding doors.

The invention has for its object to provide a door hanger with a roller device so constructed and mounted as to operate with 15 a minimum of friction and prevent jamming of the door at any place on the rail from which the door is suspended.

The invention consists of a hanger frame embodying a novel form of roller, constructed and arranged as hereinafter set 20 forth and claimed.

Referring to the drawing, Figure 1, is a vertical transverse sectional view of the door hanger mounted in position for use; 25 Fig. 2, is a perspective view of the roller and Fig. 3 is a similar view with the segments of the roller separated to show the interior construction more clearly; and Fig. 4 is a detail view of a portion of the bracket.

In carrying out my invention a bracket 1 is secured to the top of the door 16 and projects above the same. The bracket comprises base plate 2 provided with vertical sides 3, 3 and an arched top. Mounted in 35 the sides 3, near the arched top, in the threaded holes 4, 4, are laterally projecting pivot pins 5, 5, extending interiorly of the hanger frame. These pins are provided at their inner ends with cone-shaped bearing 40 points 6, 6, and the bodies of the pins are screw-threaded and adapted to be inserted in the said holes 4, 4, and to be adjusted laterally with relation to the roller 7, which is journaled on said pins. Conical recesses 45 8, 8, are provided at diametrically disposed points of the roller, to receive the points of the said pins. Set screws 9, 9, which project through the edges of the sides 3, 3 and contact with the bodies of pins 5, 5, are provided for the purpose of securing the latter 50 against movement when properly adjusted.

The roller 7 is preferably cylindrical in form and is made of segments, in this case three being shown. These segments, 10, 11 55 and 12 are spaced apart to prevent fric-

tional contact, by the interposition of balls 13, of suitable size and number, arranged in registering, circular, concaved tracks 14, formed in the opposing faces of the segments of the roller. The segments are arranged to revolve on a common horizontal axis, alined with the journal pins 5, 5. 60

The track or rail 17, which is secured to the door frame, is located inside of the bracket 1, and the central segment 11 of the 65 roller 7 travels on the upper edge thereof. The upper edge is concaved to prevent the roller from leaving the track.

Of course it will be understood that it is usual to employ a set of door hangers, which 70 comprises two.

When constructed as above described, with all friction reduced to a minimum, the movement of the door on the track is smooth 75 and it does not jam. This latter fault is usually the result of derailment.

The principal objections to sliding doors of the heavier type, are the noise and difficulty of operation. Both of these are obviated by the present invention. The formation 80 of the roller with a central segment operating independently upon the supplemental ball-bearings, makes it much easier to operate the door.

Having thus described my invention what 85 I claim as new and desire to secure by Letters Patent is:

1. In a door hanger, the combination with a bracket, of a ball-roller comprising an independently rotatable, central section 90 designed to operate on the door track, anti-friction means interposed between the sections of the roller for retaining the said central section in juxtaposition with the other sections, and studs, mounted in the 95 bracket, on which the end-sections of the roller are journaled axially.

2. In a door hanger, the combination with a bracket, of a ball-roller comprising an independently rotatable, central section 100 designed to operate on the door track, ball-bearings arranged in circular ball-races formed concentrically in the opposing faces of the roller-parts, and adjustable studs, mounted in the bracket, on which the end-sections of the roller are journaled axially.

3. In a door hanger, the combination with a bracket, of a cylindrical roller comprising a plurality of segments, one of which is located centrally to travel on the track of 110

the door frame, said segments being suitably spaced apart and provided with ball-bearings located between the opposing faces, the said segments being arranged to revolve 5 upon a common horizontal axis, and journal pins carried by said bracket and revolvably supporting the said roller.

In testimony whereof I affix my signature in presence of two witnesses.

CHARLES O. MARX.

Witnesses:

ERNEST NEITHARDT,
PETER MARX.
